UNITED STATES PATENT OFFICE.

WILLIAM A. WIGHT, OF TACOMA, WASHINGTON.

STEPLADDER.

Application filed October 29, 1924. Serial No. 746,605.

To all whom it may concern:

Be it known that I, WILLIAM A. WIGHT, a citizen of the United States, residing at Tacoma, in the county of Pierce and State 5 of Washington, have invented a new and useful Stepladder, of which the following is a specification.

This invention relates to stepladders and the primary object thereof is to construct a 10 ladder of this character which is light and strong and in which no side sway is possible.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed may be made within the scope of what is claimed without departing from the spirit of the invention.

In the accompanying drawings:—

25 Figure 1 represents a side elevation of a stepladder constructed in accordance with this invention;

Fig. 2 is a detail longitudinal section taken on the line 2—2 of Fig. 1; and 30 Fig. 3 is a detail transverse section taken on the line 3—3 of Fig. 1.

In the embodiment illustrated a step-section 1 and a brace-section 10 are hingedly connected at their upper ends by a platform 20 which is here shown fixedly secured to the step section 1 and with which the brace-section 10 is pivoted.

40 The brace-section 10 is constructed in any suitable or desired manner of the usual side bars as 11 connected and braced in any suitable manner, cross braces 12 being here shown such as are ordinarily employed in ladders of this character.

45 The step-section 1 is constructed of two sides bars 2 and 3 which are exactly alike and hence one only will be described in detail. Each of these side bars is composed of two flat boards or bars 4 and 5

between which the ends of the steps 6 are fitted and through which pass connecting 50 bolts 7 which pass also edgewise through the step ends as is shown clearly in Fig. 3.

Braces 8 are arranged between the upper face of one step and the lower face of the other between the members 4 and 5 of the 55 side bars and as shown, the lower ends of these braces 8 rest on the upper surface of one step adjacent to the ends thereof, while the upper ends thereof engage the under surface of the adjacent upper step at points 60 in spaced relation with the ends of the upper steps, thereby relieving the connecting bolts 7 of undue strain caused by persons standing on the steps of the ladder.

The usual folding braces 13 connect the 65 step and brace sections of the ladder and a bucket supporting board or platform 14 is also preferably mounted in the upper end thereof.

While this ladder is shown constructed 70 in the form of a step ladder obviously it may be in any other form, the gist of the invention residing in the peculiar construction of the step section which is so formed and braced that there is no possibility of 75 any side sway and yet the weight of the ladder is not materially increased.

I claim:—

In a ladder construction, a step section including side bars, each of the side bars 80 comprising a pair of longitudinally disposed bars, steps arranged between the longitudinally disposed bars and secured thereto, brace bars having their lower ends positioned on the upper surfaces of the steps adjacent to their outer ends, said braces having their upper ends engaging the under surfaces of the steps at points in spaced relation with the ends of the steps, and said brace members adapted to engage the longitudinally disposed bars.

In testimony that I claim the foregoing as my own, I have hereto affixed my signature.

WILLIAM A. WIGHT.
